FIG. 1 is a perspective view of a roof rack crossbar assembly for a convertible sports utility vehicle, according to my new design;

FIG. 2 is a perspective view thereof;

FIG. 3 is a top plan view thereof (mounted on vehicle);

FIG. 4 is a top plan view thereof;

FIG. 5 is a left side elevation view thereof (mounted on vehicle);

The right side elevation view is a mirror image of the left side.

FIG. 6 is a left side elevation view thereof;

The right side elevation view is a mirror image of the left side.

FIG. 7 is a bottom plan view thereof (mounted on vehicle);

FIG. 8 is a bottom plan view thereof;

FIG. 9 is a front elevation view thereof; and,

FIG. 10 is a rear elevation view thereof.

The broken lines depict unclaimed environmental subject matter and do not form any part of the claimed design.
